[57] CLAIM

The ornamental design for a portable stadium cushion,
as shown and described.

DESCRIPTION

FIG. 1 is a bottom, front, and left side perspective view
of a portable stadium cushion showing my new design;
FIG. 2 is a top, rear, and left side perspective view
thereof;

FIG. 3 is a reduced bottom plan view thereof;
FIG. 4 is a reduced right side elevational view thereof,
the left side being a mirror image of that shown;
FIG. 5 is a bottom, front, and left side perspective view
of a second embodiment thereof; and,
FIG. 6 is a top, rear, and left side perspective view of
the embodiment of FIG. 5, the only difference residing
in the configuration of the bottom.
